UNITED STATES PATENT OFFICE.

HARRY WILLIAM HILL, OF SOUTHRIDGE, MASSACHUSETTS, ASSIGNOR TO AMERICAN OPTICAL COMPANY, OF SOUTHRIDGE, MASSACHUSETTS, A VOLUNTARY ASSOCIATION OF MASSACHUSETTS.

PROCESS FOR FORMING BIFOCAL LENSES.

1,180,395.

Specification of Letters Patent. Patented Apr. 25, 1916.

Application filed October 31, 1914. Serial No. 869,680.

To all whom it may concern:

Be it known that I, HARRY W. HILL, a citizen of the United States, residing at Southbridge, in the county of Worcester and State of Massachusetts, have invented 5 certain new and useful Improvements in Processes for Forming Bifocal Lenses, of which the following is a specification.

This invention relates to improvements in 10 bifocal lenses, and has particular reference to those forms of bifocal lenses which consist of two pieces of glass of dissimilar index secured to each other as by fusion.

The leading object of the invention is the 15 provision of an improved process for securing the most satisfactory uniting of the two parts of a bifocal, and to reduce to a minimum any defect in the lens on account of said fusion.

20 A further object of the invention is the provision of an improved process which will permit of uniting the major portion of the blank and segment without the interposition of any foreign matter between the uniting faces of the blank and segment as has hitherto been deemed necessary.

Another object of this invention is the 25 provision of an improved process of uniting the main and segment portions of an ophthalmic bifocal lens blank in such manner that the entire blank may be used in the formation of the finished lens in place of a part being wasted, as is the case with the processes at present employed.

30 Other objects and advantages of this improved process of forming bifocal lenses should be readily apparent by reference to the following description taken in connection with the accompanying drawings, and 35 it will be understood that any modifications may be made within the scope of the appended claims without departing from or exceeding the spirit of this invention.

Figure I represents a plan view with the 40 parts in position for fusion. Fig. II represents a similar view after fusion. Fig. III represents a sectional view on the line III—III of Fig. I. Fig. IV represents a 45 similar view on the line IV—IV of Fig. I. Fig. V represents a sectional view on the line V—V of Fig. II. Fig. VI represents a view similar to Fig. IV but illustrating a 50 modified construction.

In the drawings, in which similar char-

acters of reference are employed to denote 55 corresponding parts throughout the several views, the numeral 1 designates an ophthalmic lens blank having suitably formed therein the countersink 2 adapted to receive the segment 3, said segment being formed from 60 glass of a different index from that of the blank 1.

In that embodiment of the process here-with illustrated the segment is formed with the beveled surrounding edge as at 4, and 65 when placed in position for fusing one or more angle pieces 5 are disposed with one face of the angle resting upon the main blank 1 and the other face of the angle bearing against the bevel 4 on the segment, 70 the angle member or members 5 being preferably secured by suitable adhesives to either the main blank 1 or the segment 3, or to both, to avoid liability of slipping. By reference particularly to Figs. III and IV, the 75 use of these members 5 will be clearly understood, and it will be seen that they serve to hold a portion of the segment slightly spaced from the face of the countersink 2, the other end of the segment resting against 80 the edge of the countersink, if desired, as illustrated in Fig. III, for example. As the parts are then heated but slight softening of the beveled edge 4 will allow the same to slide downward on the steep incline of the 85 angle member 5 and will consequently allow the segment to sink into correct position upon the main blank 1 and become properly united therewith without the presence of air bubbles or the like. The parts having 90 then been united the angle members may be readily removed without in any way disturbing the relation of the main blank and segment and without injury to either of 95 said parts.

In Fig. VI is illustrated a slightly modified form of my device in which the segment member 3 has formed thereon the projection or rib 6 adapted to be engaged by the wedge-like members 7 for holding the disk at the 100 edges and keeping it spaced from the main portion 1 of the blank. The wedge-like formation of the members 7 permits of their adjustment to retain the segment in desired relation to the main blank, while heating 105 softening of the thin member 6 will readily allow the segment to sink into correct position and engagement with the countersink

It will thus be seen that in the various forms I support the segment by means entirely out of the field of uniting or joining of the parts and by means which may be readily removed after the parts have been united and that by engaging but the edge or exterior portion of the segment there is no interference with or disturbance of the uniting surfaces of the two parts of the completed blank, and that consequently a more perfect blank for an ophthalmic lens may be produced and one not subject to the defects and strain present in those produced by prior processes.

15 I claim:

1. The process of forming a bifocal lens blank consisting in forming one of the two parts to be united with a slightly beveled edge, supporting the two parts to be 20 united in spaced relation by independent devices engaging said beveled edge, and subjecting the parts to a temperature sufficient to so soften the beveled member that it will slide downward on the support into 25 close engagement with the other section of the blank, substantially as described.

2. The process of forming a bifocal lens blank, consisting in employing a main portion, forming a countersink in said main 30 portion, forming a segment with a beveled edge, supporting said parts in spaced relation by angle members engaging the upper face of the main blank and the beveled edge of the segment, and subjecting the parts to 35 heat, whereby the beveled edge is sufficiently softened to permit the segment to slide downward on the angle members into engagement with the main blank, and subjecting the parts to a continuing heat sufficient 40 to fuse the main blank and segment into a unitary structure.

3. The process of forming a bifocal lens blank, consisting in employing a main portion, forming a countersink in said main 45 portion, forming a segment with a beveled edge, supporting said parts in spaced relation by angle members engaging the upper face of the main blank and the beveled edge of the segment, and subjecting the parts to 50 heat, whereby the beveled edge is sufficiently softened to permit the segment to slide downward on the angle members into engagement with the main blank, continuing 55 the heat sufficiently to fuse the main blank and segment into a unitary structure, and removing the angle members from the exposed faces of the main and segment por-

tions of the blank, prior to the grinding of the resultant product into a finished lens.

4. The process of forming a bifocal lens blank, consisting in forming a main blank with a countersink therein, forming a segment blank with a convex curvature approximately the same as that of the countersink, and with a flaring beveled edge adjacent the convex curvature, mounting angular spacing members on the main blank, moving said members into engagement with the flaring bevel of the segment to support the segment spaced from the main blank, 65 securing the spacing members in position, subjecting the parts to a welding temperature whereby the beveled edge is softened to allow the segment to move downward into engagement with the main blank, and 70 continuing said temperature to fuse the parts together.

5. The process of uniting blanks for a bifocal lens, consisting in securing diverging supports to one of the parts, placing the other part between the upper portions of the supports, whereby the two parts are held in spaced relation, and subjecting the parts to a welding temperature whereby one of the parts is caused to soften and 80 settle down upon and adhere to the other.

6. The process of forming a bifocal lens, consisting in polishing the two surfaces to be united, supporting the parts in spaced relation by supports engaging the side only 85 of one of the parts, and subjecting the parts to a fusing temperature whereby the sides are softened to allow the parts to move into engagement with each other and unite without bending of the polished surfaces thereof.

7. The process of forming a bifocal lens, consisting in grinding and polishing a countersink in one of the parts, forming 90 and polishing a corresponding convex curvature on the other part, supporting the parts in spaced relation by means engaging the lateral edge only of the convex part, and subjecting the parts to a fusing temperature, whereby the edge of the convex member is caused to soften and permit the member to settle down upon and adhere to the other without bending of the polished portion thereof.

In testimony whereof I affix my signature in presence of two witnesses.

HARRY WILLIAM HILL.
